UNITED STATES PATENT OFFICE

NATHAN M. LOWER, OF PITTSBURGH, PENNSYLVANIA, ASSIGNOR, BY MESNE ASSIGNMENTS, TO THE STANDARD STOKER COMPANY INC., OF NEW YORK, N. Y., A CORPORATION OF DELAWARE

LOCOMOTIVE STOKER

Application filed February 18, 1927. Serial No. 169,219.

The objects of the invention are to simplify, lighten and improve the efficiency of transferring mechanism for moving fuel from the fuel bin of a locomotive tender to a point of discharge into the firebox of the locomotive. A further object is to provide for the reduction in size of lumps of coal which are larger than it is desirable to deliver to the firebox.

10 The invention consists in a structure such as is hereinafter described and as illustrated in the accompanying drawings in which

15 Fig. 1 is a detail plan view of the rear end of a locomotive and the forward end of its tender, with the improved stoker applied thereto, some parts of the stoker mechanism being broken away and a portion thereof being shown in section;

20 Fig. 2 is a detail, central, vertical section of the rear end of the locomotive and the forward end of its tender with the improved stoker applied thereto parts of the locomotive and tender framing being conventionally indicative;

25 Fig. 3 is a detail, transverse, vertical section on the line 3—3 of Fig. 2;

Fig. 4 is a detail, transverse, vertical section on the line 4—4 of Fig. 2;

30 Fig. 5 is a detail section on line 5—5 of Fig. 4, and

Fig. 6 represents a portion of Figure 2 enlarged.

A portion of a side wall of the cab of the locomotive is shown at 10 and of the floor thereof at 10^a. The location of the firebox is indicated by the numeral 11 and a portion of the grate thereof at 13. The backhead of the boiler, forming the rear wall of the firebox is designated 12, and the usual hand firing door opening therein is shown at 12^a.

The tender is generally indicated by the numeral 14 and its fuel bin is shown at 15.

The means for advancing the fuel from the tender to the firebox comprises a plurality of endless drag chains 16, shown as four in number, housed within a casing 17 substantially U-shaped in cross section, having side walls and a bottom. This casing may be and preferably is formed of a single plate 50 of sheet metal bent to the desired form. It

extends backwardly under the fuel bin and forwardly approximately to the fire door opening 12^a, such forward end being inclined upwardly, when, as in the form of construction illustrated, the firing door opening is at 55 a greater elevation than the necessary location of the rearward end of the casing below the tender floor.

Each of the chains 16 turns about a pair of wheels, 60, 18, preferably sprockets, the former being mounted upon a shaft fixed across the rear end of the casing and the latter being mounted upon a bar fixed across the forward end of the casing. Preferably these wheels are loosely journaled on their 65 respective shafts and are spaced apart and from the side walls of the casing by sleeves as shown at 19.

The chains are driven by means of sprocket wheels 20 fixed upon a shaft 21 journaled in 70 the side walls of the casing 17, intermediate of its ends, the sprocket wheels 20 engaging both the upper and lower turns of the chains.

In order to prevent the sagging of the chains and to hold them in driving engagement with the wheels 20, each is provided with a plurality of laterally extending lugs 22, running in lateral grooves in longitudinal bars 23 mounted within the casing and carried by plates 24, 25 located respectively 75 80 immediately below the upper turn and above the lower turn of the chains and secured to the side walls of the casing 17 as by means of angle bars, 26. The upper plate 24 and the side walls of the casing constitute a fuel conduit.

The floor of the fuel bin of the tender is apertured as indicated at 27 above the casing 17, such aperture extending preferably from the rear end of the bottom of the bin to or 90 beyond the coal gate 28, thereby permitting the fuel to fall by gravity upon the upper turns of the chains. In order to prevent the loss of fuel between the sides of the casing 17 and the bottom of the fuel bin, a pair of 95 angle bars 29 flank the aperture 27, their horizontal flanges slidably engaging the bottom of the bin floor, their vertical flanges slidably engaging the outer faces of the casing walls. These bars are suitably anchored to the casing 100

as indicated at 30, in order that they may not move longitudinally or laterally with the casing but have a certain freedom of relative vertical movement. They are urged upwardly against the fuel bin floor by springs as 31, 31 and 32, 32 which react between their horizontal flanges and suitable brackets carried by the casing.

A fuel delivery nozzle 33 is bolted to the backhead 12 as shown at 34 and projects into the lower portion of the firing opening 12^a as shown in Fig. 2. The shaft or rod 35, upon which are mounted the forward set of wheels 18, serves as means for movably attaching the casing 17 to the nozzle 33. For this purpose the ends of the rod 35 are rounded to approximate sections of spheres as shown at 36, 37, seated within complementary recesses formed in the inner faces of the side walls of the nozzle. As shown, the lower portion 38 of the nozzle 33 consists of a separate casting which may be bolted to the backhead and is also bolted to the upper section of the nozzle as shown at 39. The concave recesses 25 for receiving the rounded ends 36, 37 of the shaft are formed in part in each of the two sections of the nozzle. This form of attachment of the casing 17 to the nozzle 33 constitutes a ball and socket joint thereby permitting flexure due to the relative movement of locomotive and tender. In order to permit movement of the rear end of the casing 17 due to changes in the relative positions of the locomotive and tender, the casing is supported by a pair of flat faced wheels 40, 41 running on shelves 42, 43 secured to the frame members of the tender. The wheels 40, 41 are journaled on trunnions 44, 45 projecting from bosses 46, 47 rigidly secured to the side walls of the casing 17. As shown in Fig. 4, the bosses 46, 47 serve conveniently as seats for the rearward pair of springs 31, 31 supporting the angle bars 29, 29.

The nozzle 33 discharges upon a distributor plate 48 which projects through the firing door opening 12^a and is provided at its rearward end with a steam box 49 having ports arranged to discharge jets over the face of the plate for throwing fuel therefrom and scattering it over the area of the grate 13. The shaft 21 carrying the driving sprocket wheels 20 is turned by power derived from a suitable motor 50 mounted upon the frame of the locomotive, the driving connection comprising a telescopically extensible shaft 51 and a pair of bevelled gears, 52, mounted upon such shaft, and 53 mounted on the shaft 21.

When, as in the construction illustrated, the forward end of the casing 17 is inclined upwardly, another set of idler sprocket wheels 54 is mounted within the casing 17 at the juncture of its horizontal and inclined sections, these wheels engaging both the upper and lower turns of the chains 16.

For the purpose of reducing the fuel, when

necessary, to proper size for feeding, a longitudinally ribbed crushing roller 55 is journaled in suitable brackets 56, 57 rising from the floor of the fuel bin and preferably located in line with the fuel gate 28. Lumps of coal too large to pass under this roller are forced against it by chains 16, causing it to turn and accomplish the crushing action. A shield plate 55^a is preferably attached to the coal gate 28 and depends over the crusher roller 55 for the purpose of preventing accidents to the fireman.

A section of the floor 10^a of the cab may be inclined upwardly as shown at 58 to cover the forward end of the casing 17 and desirably this section is detachably secured to the rear end of the top of the nozzle 33.

The chains are provided with spurs or lugs as 59 for urging the fuel forward.

The fuel in the bin rests by gravity upon the rear portions of the chains 16 which are beneath the aperture 27. The chains carry forwardly the lower stratum of the fuel, passing it under the crushing roller and delivering it to the nozzle 33 and upon the distributor plate 48. Should clogging occur, as by the presence in the fuel of extraneous matter such as pieces of rock or metal, the direction of movement of the chains may be reversed by reversing the motor for the purpose of disengaging them. Such clogging may occur at the crushing roller but is not apt to occur at any other point.

Inasmuch as the fuel transferring mechanism is of considerably less width than the fuel bin, the operator may have access to the fuel at either side of the bin should hand firing become necessary.

While a practical and preferred form of construction is shown and described, various changes may be made therein within the scope of the invention.

I claim as my invention:

1. The combination with a locomotive and its tender, the latter having an opening in its floor, of a casing flexibly attached to the backhead of the locomotive and projecting under the floor of the tender and being free to move relatively thereto, its rearward portion being open to receive fuel through an aperture in the tender floor, an endless conveyor in the casing, and means for driving the conveyor.

2. The combination with a locomotive and its tender, the latter having an opening in its floor, of a casing flexibly attached to the backhead of the locomotive and projecting under the floor of the tender and being free to move relatively thereto, its rearward portion being open to receive fuel through an aperture in the tender floor, a plurality of endless drag chains mounted within the casing, and means for driving the chains.

3. The combination with a locomotive and its tender, the latter having an opening in its floor, of a casing flexibly attached to the back-

head of the locomotive and projecting under the floor of the tender and being free to move relatively thereto, its rearward portion being open to receive fuel through an aperture in the tender floor, a plurality of endless drag chains mounted within the casing, shafts adjacent to the ends of the casing for carrying the chains, and means for driving the chains.

4. The combination with a locomotive and its tender, the latter having an opening in its floor, of a casing flexibly attached to the backhead of the locomotive and projecting under the floor of the tender and being free to move relatively thereto, its rearward portion being open to receive fuel through an aperture in the tender floor, a plurality of endless drag chains mounted within the casing, shafts adjacent to the ends of the casing for carrying the chains, the forward shaft being comprised in the means for attaching the casing to the backhead, and means for driving the chains.

5. In a locomotive stoker, in combination, a delivery nozzle adapted for fixed attachment to the backhead of a locomotive boiler and to deliver to an opening therein, a transfer conduit pivotally attached to the nozzle and adapted to project under the floor of the tender of a locomotive, a plurality of endless drag chains the upper turns thereof traveling over the floor of the conduit, laterally channeled bars flanking each chain, lugs carried by the chains engaging the bar channels and driving sprocket wheels engaging the chains intermediate of the ends of the conduit.

35 6. In a locomotive stoker, in combination, a transfer conduit, a set of endless drag chains within the conduit rollers mounted adjacent the ends thereof over which the chains turn, laterally channeled bars flanking each chain, lugs carried by the chains and engaging the bar channels, and driving sprocket wheels engaging the chains intermediate of the rollers on which they are mounted.

7. In a locomotive stoker, in combination, a transfer conduit, a set of endless drag chains within the conduit rollers mounted adjacent the ends thereof over which the chains turn, laterally channeled bars flanking each chain, lugs carried by the chains and engaging the bar channels, and driving sprocket wheels mounted below the conduit floor and engaging both runs of the chains intermediate of the rollers on which the chains are mounted.

8. In combination, a locomotive having a fire box, a tender having an opening in its floor, a transfer conduit pivotally attached to the backhead of the fire box and projecting under the floor of the tender and being free to move relatively thereto, endless drag chains running in the conduit, a pair of angle bars attached to the rearward portion of the conduit, one flange of each angle bar slidably engaging a side wall of the conduit and one flange thereof slidably engaging the lower surface of the tender floor adjacent the open-

ing therein, and means for urging such bars against the floor of the tender.

9. In combination, a locomotive having a fire box and a firing opening in the backhead thereof, a distributor plate projecting through the lower portion of such opening, a steam nozzle at the rear end of the plate and discharging thereover, a fuel nozzle attached to the backhead and delivering upon the plate, a tender having an opening in its floor, a transfer conduit pivotally attached to the nozzle and projecting under the tender and being free to move relatively thereto and being upwardly open in its rearward portion to register with the floor opening, a series of endless drag chains extending from end to end of the conduit, means for driving the chains, and a freely rotatable crushing roller mounted adjacent the forward end of the floor opening and cooperating with the chains.

10. In a locomotive stoker, in combination, a fuel delivery nozzle adapted for attachment to the backhead of a locomotive, a transfer conduit, a rod extending across the forward end of the conduit and having its ends rounded to engage and turn in complementary recesses in the side walls of the nozzle, endless drag chains mounted within the conduit and turning about the named rod.

11. In a locomotive stoker, in combination, a fuel delivery nozzle for attachment to the backhead of a locomotive, such nozzle comprising two sections having in their side walls mating cavities together forming approximately segments of a sphere, a fuel transfer conduit delivering to the nozzle and attached thereto by a rod having its ends rounded to engage the named cavities.

12. In a locomotive stoker, in combination, a fuel delivery nozzle for attachment to the backhead of a locomotive, such nozzle comprising two sections having in their side walls mating cavities together forming approximately segments of a sphere, a fuel transfer conduit delivering to the nozzle and attached thereto by means of lateral rounded bearing surfaces engaging the named cavities.

In testimony whereof I affix my signature.
NATHAN M. LOWER.
